JAMES P. NEILSON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

SWITCH MECHANISM FOR ELECTRIC-LAMP SOCKETS AND THE LIKE.

No. 845,476.

Specification of Letters Patent.

Patented Feb. 26, 1907.

Application filed July 25, 1906. Serial No. 327,606.

To all whom it may concern:

Be it known that I, JAMES P. NEILSON, a citizen of the United States of America, and a resident of Bridgeport, in the county of

5 Fairfield and State of Connecticut, have invented a certain new and useful Improved Switch Mechanism for Electric-Lamp Sockets and the Like, of which the following is a specification.

10 My invention relates to a switch mechanism particularly intended for electrical lamp sockets, but which may be used in any electrical appliance in which a contact is made or broken by means of a contact-piece operated with lost motion by a spindle.

15 My device has for its object that the operating-shaft and the contact-piece shall tend to maintain practically the same positions relatively to each other at all times.

20 In the accompanying drawings I have shown my invention incorporated in a standard incandescent-lamp socket.

25 In the accompanying drawings, Figure 1 is a vertical section of a portion of an incandescent-lamp socket in which my device is applied, and Fig. 2 is an enlarged perspective view of the spindle and contact-piece therein.

As ordinarily constructed the spindle and its operating-key in an incandescent-lamp

30 socket may freely occupy any position within the arc of lost motion relative to the position of the contact-piece. Inasmuch as this arc is considerable, extending over as many as seventy degrees in some cases, it is difficult

35 to be sure from the position and angle of the key what the position of the contact-block within the socket may be. It is sometimes necessary, consequently, to revolve this spindle experimentally to determine whether

40 the contact is made or broken. My device obviates this disadvantage by means as simple as they are efficacious. I use a spring—for example, a tempered spring-wire 3—which at one end is connected to the spindle

45 6 and at the other to the contact-piece 5. In the present instance the wire passes through a hole drilled through the axis of the spindle at right angles to the lugs 4, which engage the contact-piece 5 on revolution of

50 the spindle 6. The equal-length arms of the spring are bent in the same direction into a

position approximately parallel to the spindle, and their free ends are then connected by any suitable means, as by inserting them in holes drilled to receive them in the opposite ends of the contact-piece. The operation of this spring is plain. Whatever the position of the contact-piece, the spring under torsional strain revolves the spindle through the arc of lost motion until the axis of the hole 55 in the spindle through which the spring passes is in the same plane as the longitudinal axis of the contact-piece. The web 7 of the spindle, therefore, if attached in the plane of the hole through which the spring 60 passes furnishes a ready indicator of the position of the contact-piece, which lies in the same plane.

I claim as my invention—

1. An electrical switch device having a 70 spindle and a contact-piece connected with lost motion to said spindle, and directly operated by the latter with means tending to keep said parts in the same positions with relation to each other rotarily.

2. A key-socket having a spindle and a contact-piece connected with lost motion to said spindle, and directly operated by the latter with spring means tending to keep the spindle and contact-piece in the same positions with relation to each other rotarily.

3. A key-socket having a spindle, a thumb-key and a contact-piece connected with lost motion to said spindle and directly operated by the latter with a spring connecting the spindle and the contact-piece tending to keep them in the same position with relation to each other rotarily.

4. A key-socket having a spindle and contact-piece connected with lost motion to said spindle, with a spring connecting the spindle and contact-piece and secured to the latter on opposite sides of the spindle, substantially as described.

90 In testimony whereof I have signed my 95 name to this specification in the presence of two subscribing witnesses.

JAMES P. NEILSON.
